UNITED STATES PATENT OFFICE.

MARTIN LANDENBERGER, OF PHILADELPHIA, ASSIGNOR TO HIMSELF, MARTIN LANDENBERGER, JR., AND CHAS. H. LANDENBERGER, OF SAME PLACE, AND CHAS. WEILER, OF LANDENBERG, PENNSYLVANIA.

DESIGN FOR JACKETS.

Specification forming part of Design No. 7,831, dated November 3, 1874; application filed July 16, 1874.
[Term of Patent 3½ years.]

To all whom it may concern:

Be it known that I, MARTIN LANDENBERGER, of Philadelphia, Pennsylvania, have invented a Design for a Lady's Jacket or Vest, of which the following is a specification:

In the accompanying drawing, Figure 1 represents a design for a pattern for a lady's jacket or vest; and Fig. 2, a view of the pattern folded.

The pattern A has parallel sides *a a*, a V-shaped projection, *b*, at one end, and a corresponding V-shaped recess, *d*, at its opposite end, the latter merging into a rounded opening, *e*, which, when the pattern is folded, as shown in Fig. 2, forms the neck-hole of the jacket or vest, the sides *a a* meeting the in-

clined edges *ff* of the portion *b* of the pattern to form the sides of the vest, while the edge *h h* meet at the front of the latter.

I claim—

The design for a lady's jacket or vest, having parallel sides *a a*, a V-shaped projection, *b*, and a V-shaped recess, *d*, merging into a rounded opening, *e*, as shown and described.

In testimony whereof I have signed my name to this specification in the presence of two subscribing witnesses.

MARTIN LANDENBERGER.

Witnesses:

WM. A. STEEL,
HUBERT HOWSON.
